CONDENSER AND MOUNTING THEREFOR

Richard U. Clark, Wilmette, Ill., assignor, by
mesne assignments, to The Magnavox Com-
pany, Incorporated, a corporation of Indiana

Original application November 10, 1936, Serial No.
110,098. Divided and this application April 23,
1937, Serial No. 138,495

1 Claim. (Cl. 248—27)

The present invention relates to a novel com-
bination of condenser and mounting or support
therefor.

Among the objects of the present invention is
5 to provide a combined condenser and mounting
therefor for maintaining the condenser in a pre-
determined adjusted horizontal position and in
axial alignment with the mounting. The present
application is a division of my pending applica-
10 tion Serial No. 110,098, filed November 10, 1936.

A further object is to provide a combined con-
denser and mounting therefor adapted to main-
tain the condenser in a predetermined longitudi-
nal adjusted position and in axial alignment
15 with the mounting without fixing the condenser
to the mounting and which will at the same time
permit hand pressure mounting and demounting
without the use of tools and the like.

The above features, advantages and capabilities
20 of my present invention will become apparent
from a description of the accompanying drawing
in which I have illustrated one form of my inven-
tion but the form there shown is to be under-
stood as illustrative only and not as defining the
25 limits of my invention except as expressed or in-
tended to be expressed in the appended claim.

In the drawing:

Fig. 1 is a view in perspective of the novel con-
denser and mounting therefor.

30 Fig. 2 is a vertical cross sectional view of the
condenser and a top plan view of the mounting.

Fig. 3 is a view in vertical cross section
through the novel mounting and showing a frag-
ment of the condenser and chassis or frame of
35 a radio.

Fig. 4 is a fragmentary view in side elevation
of the shell or casing, while Figs. 5 and 6 are
alternate forms of the condenser shells or casings.

Referring more particularly to Figs. 1 to 4 in-
40 clusive, of the drawing, the mounting device 1
which is adapted to support the condenser 2 in a
predetermined position comprises a metal base or
supporting member 3 provided with a central
opening for receiving the body of the condenser.

45 In its preferred form, this base is flat and of an
annular shape or configuration, although it is to
be understood that various shapes or configura-
tions may be utilized. Projecting from the base
in opposed directions are sets of longitudinally
50 spaced members 4 and 5 with the one set dis-
posed in staggered relation with respect to the
gripping members in the other set. These mem-
bers are constructed of metal, preferably steel,
and project inwardly and provide resilient grips
55 adapted to mesh firmly with the concave corru-
gations formed in the condenser 2 for firmly grip-
ping the condenser and normally maintaining it

in suspension and in axial alignment with the
chassis or pan 6 upon which it is supported, with-
out any additional or auxiliary supporting or
retaining means. The construction and arrange-
ment of these gripping members is such that al-
though the condenser is firmly retained against
accidental removal or displacement, they at the
same time permit the ready intentional pressure
mounting or demounting of the condenser. 5

In the disclosed embodiment of the invention, 10
the outer shell or casing of the condenser is pro-
vided with one or more spaced annular concave
corrugations 7 into which one or both sets of the
members 4 and 5 seat when the condenser has
been forced into the opening in the mounting to 15
the desired extent or position.

In Figs. 5 and 6, I disclose alternate forms of
the shell or casing in which may be provided but
one annular corrugation 8 and longitudinally
spaced depressions 9 suitably spaced apart to 20
register and mesh with the ends of the lower
members 5, or longitudinally spaced depressions
10 and 11 arranged in staggered relation to regis-
ter and mesh with the ends of both the upper and
lower resilient gripping members. 25

When utilizing the novel construction, the
suspension mounting is preferably first pressed
into a suitable opening provided in the pan or
chassis 6 of a radio set or the like, and retained
therein by a gripping pressure of the lower mem-
bers against the periphery of the opening as more
30 clearly disclosed in Fig. 3. The condenser is then
grasped in the hand and forced into the opening
in the mounting by pressure until the members
are brought into registration and mesh with the
35 concave corrugations formed.

From the above description and the disclosure
in the drawing it will be readily apparent that
the invention comprises a novel construction of
40 condenser and mounting therefor, in which the
condenser is retained in a suspended position by
a resilient but firm gripping pressure which pre-
vents accidental or unintentional displacement or
removal. 45

Having thus disclosed the invention,

I claim:

In a device of the class described, the combina-
tion of a condenser and a mounting therefor pro-
vided with opposed sets of reversely curved resili-
ent gripping members at their free ends adapted
to resiliently but firmly grip the condenser, and
circumferentially arranged spaced recesses
formed in the wall of the condenser to receive
the gripping members substantially as and for the
purpose set forth.

RICHARD U. CLARK.
